LIQUID FILLING VALVE

Everett S. Minard, San Francisco, Calif., assignor,
by mesne assignments, to The Pfaudler Co.,
Rochester, N. Y., a corporation of New York

Application May 16, 1941, Serial No. 392,923

2 Claims. (Cl. 226—124)

The present invention relates to improvements in liquid filling valves, and its principal object is to minimize the aeration of the liquid in the filling process.

More particularly the invention relates to container-operated filling valves in which the liquid is arranged in a large tank provided with one or more downwardly projecting conduits having valves at their lower ends which are adapted to be opened by the raising of the container against the valves whereby the liquid is discharged into the container.

In valve structures of this type, the container makes an air-tight seal with the valve structure during the filling operation and a vent is provided to allow the air to escape from the container while the liquid flows thereinto.

With many liquids it is desirable to keep the liquid out of contact with air as much as possible and it has been difficult to arrange the vent with respect to the valve opening in such a manner that the vent would take care of all displaced air during the filling operation, particularly toward the end of the latter.

In most machines developed for this purpose, a certain amount of air becomes trapped, particularly toward the end of the operation, and instead of having free access to the vent is made to gurgle back through the valve opening and to rise through the liquid in the conduit and through the liquid in the tank before reaching the atmosphere.

In the present invention it is proposed to prevent this occurrence, and to provide a valve structure which keeps access of displaced air to the vent open until the container is filled to its capacity so that all the air is made to escape through the vent rather than through the valve opening.

It is further proposed to provide a valve structure in which the inflow of liquid into the container stops when the level of the liquid reaches the vent, so that the liquid cannot rise to a level higher than the vent intake.

In structures of this type, it is usual to employ a poppet valve, which, when open, showers the material into the container in the form of an annular curtain. Since the vent is preferably arranged in the center of the valve, for instance in the form of a hollow valve stem, the annular curtain of descending liquid forms a closure around the vent so as to shut off access for air disposed outside the curtain.

It is a particular object of the present invention to overcome this difficulty by breaking the

curtain of descending liquid at various points and to provide passage ways which guide air from the outside of the curtain through the latter and toward the vent.

It is further proposed to provide a valve structure in which the final outlet opening of the valve is restricted as compared with the cross-section of the conduit leading to the valve, so that the liquid is made to pass through the valve opening as a solid mass which further tends to discourage air from rising through the valve opening.

In my valve structure a small amount of air is trapped underneath the sealing means and the space occupied by this air is filled after the seal is broken. In order to effect complete filling of the container and even filling of a large plurality of containers, it is essential to provide a nice adjustment whereby the amount of entrapped air may be controlled, and it is a further object of my invention to provide such adjustment.

And finally it is proposed to provide an improved mounting means for a sealing washer which firmly retains the latter in place, but also allows of easy removal of the same.

Further objects and advantages of my invention will appear as the specification proceeds, and the novel features of the same will be fully set forth in the claims hereto attached.

The preferred form of my invention is illustrated in the accompanying drawing, in which:

Figure 1 shows a vertical section through the valve structure with the valve closed and the container withdrawn from the sealing washer;

Figure 2, a vertical section through the same valve, with the valve opened by a container pressed against the sealing means from below; and

Figure 3, an isometric view of the valve head.

While I have shown only the preferred form of my invention, I wish to have it understood that various changes or modifications may be made within the scope of the claims hereto attached, without departing from the spirit of my invention.

Referring to the drawing in detail, a filling tube or conduit 1 is secured to a supply tank, the bottom of which is indicated at 2. The filling tube is suspended vertically from the bottom of the tank and is open at the top to receive liquid supply from the tank.

The tube is held in place by means of a lock nut 3 which draws a bevelled projection 4 of the filling tube against the tank bottom to make a tight seal between the tank and the tube.

A pair of arms 5 arranged in the form of a yoke and formed integral with the filling tube support a boss 6 in axial alinement with the filling tube and above the latter. The arms leave ample space, as indicated at 7, to allow liquid to run from the tank into the tube.

A valve sleeve 8 is slidably mounted on the filling tube and its downward motion on the tube is limited by a valve head 9 which latter is supported by the valve stem 10 secured in the boss 6, the stem 10 being hollow so as to serve as a vent.

The valve sleeve 8 and the valve 9 have co-operating bevelled faces 12 and the valve sleeve, which will be hereinafter referred to also as the valve seat, is normally forced into valve-closing position by the spring 11, and then forms a closure for the tube 1.

A rubber sealing ring 13 is positioned on the valve sleeve 8 by means of a backing plate 15 which is threaded upon the valve sleeve and locked in place by the lock nut 16. The sealing ring is held in place by an annular series of lugs 14 extending downwardly from the plate 15 on the outside of the rubber ring, and having small projections catching underneath the rubber ring.

The backing plate 15 can be screwed upward or downward to determine the location of the sealing ring 13 on the valve sleeve.

The vent or hollow stem 10 is open through the head of the valve and its upper end extends above the level of the liquid in the supply tank.

The lower end of the valve sleeve 8 has an annular flange 18' suspended therefrom, the said flange being spaced from the valve head so as to form an annular chamber 18 therewith. This chamber forms a continuation of the valve opening and extends the valve passage to the bottom of flange 18'. The lower surface of the valve head has a plurality of inverted channels 17 mounted thereon radially, the outer ends of the channels projecting into the annular chamber 18 to within close proximity of the flange 18'. The inner ends of these channels lead to, and stop short of the open end of the vent tube 10.

The container 19 is shown as somewhat larger in diameter than the flange 18', and as being adapted to bear against the rubber ring or washer 13 for raising the valve sleeve when the container is raised by means of the platform 20.

The operation of my valve structure is as follows:

Liquid flows from the supply tank 2 into the tube 1 which is normally closed at the bottom by the valve head 9.

A container is placed on the lifter 20 in axial alinement with the valve and underneath the rubber ring or washer 13. The lifter is then raised so as to push the upper edge of the container against the washer 13 and to thereby seal the top of the container 19. Upon continuation of the upward movement, the container compresses the spring 11 and lifts the sleeve 8 from the valve head 9 so as to open the valve.

The container is stopped in its upward movement when the lower edge of the sleeve 8 is in a horizontal plane with the under surface of the channels 17, as shown in Figure 2.

Liquid begins to flow from the tube 1 into the container as soon as sleeve 8 leaves the head 9, and the backs of the channels split the liquid, which issues from the valve opening in the form of an annular curtain or cone, into a plurality of separate streams. This allows the air from outside the curtain to freely pass through the

channels toward the inside and toward the vent tube 10 for escape therethrough.

The liquid fills the container to the bottom edge of the sleeve 8, and at this point the air which remains outside the flange 18' cannot escape through the tube 10 and is compressed between the rubber seal and the liquid. This gives the desired amount of fill in the container, as the amount of air so trapped is controlled by the adjustment up or down of the sealing washer 13 on the sleeve 8.

When the valve first opens, the air that is in the annular chamber 18 of the valve sleeve 8 is pushed downward by the pressure of the liquid, and this air does not pass through the liquid and the valve opening into the tank 2. This is for the reason that the tube 10 is open and supplies the path of least resistance for the escape of the air.

The valve should be constructed so that the space for the liquid through the tube 1 and past the head 9 is greater in area than the space between the channels in the annular chamber 18. This causes the liquid to pass in a solid mass or flow between the channels into the container and prevents air from working upward between the channels into tube 1 and so through the liquid into the tank 2.

When the container is filled to the desired level, having allowed no air to escape through the valve other than through tube 10, the container is lowered from the valve, and spring 11 closes the latter.

Any liquid that has passed into the tube 10 at the end of the filling operation, drains back into the container as soon as the seal is broken. Adjustment of the rubber 13 is made to compensate for the run back liquid so that the container will be filled with the desired amount.

The lugs or prongs 14 are provided to keep the rubber washer from falling away from the valve, and they are sufficiently close on plate 15 to furnish a good hold for the washer and sufficiently spaced to allow a prying tool to be inserted between the washer and plate 15 for removing the washer.

I claim:

1. In a container-operated liquid filling means, a vertical conduit having means for feeding a liquid therethrough and having a movable valve seat at its discharge end, and a valve supported in said conduit in cooperative relation to the valve seat and having a hollow central stem to serve as a vent, the valve seat being operable by a container for raising the seat to form a liquid passage into the container for filling the latter and having a depending annular flange surrounding the valve inside the container to guide the liquid downward in the form of an annular curtain spaced from the container wall and to form a trap with the container wall, the valve having a bottom face substantially level with the bottom edge of the flange when the valve seat is raised whereby the air in the container is guided for escape through the vent until the liquid rises sufficiently high to reach the bottom face of the valve and for the flange to trap the remaining air, and the valve having inverted channels projecting horizontally into contact with the flange to divide the descending curtain of liquid and to provide vent passages from the wall of the container to the vent.
2. In a container-operated liquid filling means, a vertical conduit having means for feeding a liq-

uid therethrough and having a movable valve seat at its discharge end, a valve supported in said conduit in cooperative relation to the valve seat and having a hollow stem to serve as a vent, the valve seat being operable by a container for raising the seat to form a liquid passage into the container for filling the latter and having means cooperating with the valve to form a downward continuation of said passage for causing the liquid to drop in the form of an annular curtain spaced from the container wall, the vent being posi-

10
5
tioned to remain available for venting until the valve passage is sealed by the rising liquid whereby venting through the valve opening is substantially prevented, and the valve having radial guide channels extending to the outer circumference of the passage and adapted to divide the annular curtain of liquid dropping from the valve passage and to guide displaced air from the margin of the container toward the vent.

EVERETT S. MINARD.
